UNITED STATES PATENT OFFICE.

JOSEPH L. HUTCHINGS, OF OLEAN, NEW YORK.

DRAIN DEVICE.

Application filed August 15, 1925. Serial No. 50,424.

This invention relates to an improved faucet or drain device of simple and inexpensive construction more particularly adapted to be used on the inside of a container.

Wherever liquids, such as oil, gas, water, etc., are stored in containers, or tanks, which are either stationary or portable, a great deal of difficulty and inconvenience has been experienced when the ordinary faucets or drain devices attached to the outside of these liquid containers froze during the winter time. In many instances the liquid would freeze within the drain device located outside of the container with a consequent burst of the drain and the loss of a considerable portion of the liquid, and not infrequently all of the liquid, which would escape from the container before the leak could be repaired. In the case of stationary containers, for example oil tanks, the usual practice has been to bury the draining device attached thereto in a suitable hole, or box, filled with heat-insulating material, such as manure, etc. Even in the case of these buried and insulated drain devices, they frequently freeze and then burst with a consequent loss of at least a considerable portion of the liquid, if not all, before the leak can be repaired. There has therefore been a marked need for a draining device of simple and inexpensive construction which would be adaptable to use and operation within the tank, instead of outside the tank. It was with this need in mind that I invented this new and novel draining device as a continuation in part of my drain device described and claimed in my application filed June 6, 1925, Serial No. 35,499.

In this improved drain device I employ a pipe nipple with a lateral vent near one end, which is properly attached to the inside of the liquid container. I also use a cap to fit over, or a plug to fit into, that end of the nipple having the vent. When the cap, or plug, is turned beyond the vent, so that the vent is open, the liquid from the container can rush through the vent into the pipe nipple and thus be conveyed to some suitable place outside of the container. In order to operate the cap or plug at the end of the nipple, a stem-turning arrangement may be inserted from the outside of the container through the nipple into a suitable socket within the far, enclosed, end of the cap or plug. Thus, in order to open the

vent for the escape of the liquid within the container, the stem may be inserted through the nipple into the cap, or plug, socket and turned in order to open the vent. If desired, the stem may then be either completely withdrawn, or at least withdrawn completely from the inside of the nipple so that the escaping liquid may have full advantage of the entire inside of the nipple leading to the outside of the container.

The means on the outside of the container connected with the nipple (or plug) arrangement on the inside of the container may be of varying construction. In the preferred embodiment of my invention I prefer to have the stem operate within a bushing connected to a T located between the bushing and a pipe nipple properly attached to the container and in alignment with the nipple attached to the inside of the container. With this arrangement the stem may be either permanently attached, or not, to the cap or plug within the container. In the event that it is desired to withdraw the stem, for one reason or another, after the vent has been closed, the same may be removed from the outside connections by unscrewing the bushing from the T. The opening thus made vacant by the removal of the bushing can then be closed with an ordinary plug of proper size. Should the stem be removed in this manner the draining device would then be left in a substantially fool-proof condition. This is often a very desirable feature in the case of tanks containing large and expensive amounts of valuable liquids. The contents of the tank may be drained off through the T into any appropriate line, receptacle or what-not, as desired. On the other hand the container itself could be filled by forcing the liquid from the outside into the T and thence from the nipple arrangements through the vent into the container.

A study of this invention will show that it will lend itself to certain variations. Thus, instead of the vent being located in the far end of the inside of the nipple on the inside of the container, the vent could, instead, be placed in the cap or plug. Again, both the cap (or plug) or nipple might each have a vent or vents. Instead of the plug or cap being operated from within, it might be operated by some means located on the outside of the cap or plug. Thus the cap or plug might be operated to

open and close the vent by some means extending down through the container on the top or side of the tank. Caps and plugs of various designs could be used. In fact a solid 5 plug would lend itself to operation with this device in case the vent were placed in the nipple. As already intimated, the stem used to turn the cap or plug from within the drain device can be either detachable or 10 non-detachable, as desired.

In order to make it impossible to completely separate the cap or plug from the nipple member, I prefer to have a guard of appropriate length attached to the tank or 15 about the nipple so that when the vent is in the open position the cap or plug will bear against the far end of this guard. Other means could, of course, be employed for this purpose. 20 In order to keep the nipple permanently attached to the wall of the container, so that it will not turn when the cap or plug is rotated about the other end of the nipple in order to open and close the vent, a lock 25 washer may be employed about the nipple.

In many instances, such as in the oil industry, it is desirable to drain the contents of containers from different levels. Thus, 30 for example, it might be desired to drain off a stratum of liquid, let us say a foot or two feet, etc., from the bottom of the container. In order to make this possible I may use the above described draining device in combination with a chamber equipped with an 35 adjustable conduit to be led to the level desired as shown in Fig. 4. This chamber, which may be a cylinder of appropriate size, is located about the vent and cap or 40 plug in such a way that the liquid immediately adjacent the chamber cannot leak into it unless the adjustable conduit is placed at that level. This chamber may be attached to the nipple between the vent and 45 the wall of the container, or, indeed, it might be attached to the wall of the container, itself. The chamber is so designed that the cap or plug may be inserted into the chamber after the chamber has been put 50 into position about the vent. This can be accomplished by having the end of the chamber nearest to the cap or plug made removable. The adjustable conduit leading 55 to the chamber is preferably located at or near that end of the chamber attached to the nipple or wall of the container. This is done in order to remove as much strain as possible from the point of attachment of the chamber with the nipple or wall of the 60 container. The adjustable conduit may be of any appropriate design suitable for raising or lowering it to different levels within the container.

This invention is more particularly illustrated in the accompanying sketches.

Figure 1 is a cross-sectional view of the improved drain device attached to the inside of a tank. The stem is shown inserted into the cap.

Figure 2 is likewise a cross-sectional view, showing the vent in the open position with the cap resting against a guard to prevent the complete disengagement of the cap from the nipple. The stem is shown removed from the inside of the nipple. 75

Figure 3 illustrates the use of a cap and nipple with the vent in the cap.

Figure 4 is a cross-sectional view similar to Figure 2, but illustrating the use of a chamber surrounding the cap and vent. 80

Figure 5 illustrates the use of a plug fitting into a nipple, the nipple having the vent.

Figure 6 shows the use of a plug with the vent in the side thereof, and a nipple. 85

The container, or tank, is shown in part section. 1 is the bottom and 2 is a side wall. The nipple 3 fits into a flange-fitting 4 attached to the wall 2 by the rivets 5. The nipple 3 has a vent, or vents, 6 which can be opened or closed by the cap 7, or plug 8. A guard 9 is suitably attached about the nipple 3 and against the flange-fitting 4 by the lock washer 10, which not only holds the guard in place, but which also serves to prevent the nipple 3 from turning loose in the flange-fitting 4, when the cap 7 is made to turn in order to open and close the vent 6. The nipple 3 is threaded at both ends to receive the cap or plug, as well as to fit into the flange-fitting next to the cap. These threads are suitably tapered so that the nipple can be drawn tightly, and leakably, into the flange-fitting, and so that the cap, or plug, may be tightly drawn about, or into, the nipple to prevent any leakage from the vent 6. The cap 7 and the plug 8 are suitably equipped with either holes or sockets 11 to fit the stem 12, which is to move a cap or plug to open or close the vent. The stem 12 is equipped with a suitable turning handle, or wheel, 13 to turn the stem when it is fitted into the socket 11. The stem 12 is snugly fitted into the bushing 14, the cap 15, and the packing 16, to prevent any leakage. 105

The bushing 14 is fitted into the T 17, and the T is appropriately fitted onto a nipple 18, which in turn fits into the flange-fitting 4 attached to the container walls by the rivets 5. The T 17 has a lead-off drain 19, which leads to any suitable place or receptacle. The stem 12 is equipped with a head 20, which is adapted to fit into socket 11. On the other hand, if desired, the stem 12 may be permanently attached to the cap 7, or plug 8. In the event that it is desired to have the stem detachable from the cap or plug, the stem may be withdrawn from 110 115 120 125 130

the socket 11 and nipple 3 until the head 20 rests back against the bushing 14. In this manner, the nipples 3 and 18 may be kept wholly clear on the inside, when the vent 6 has been opened to allow the inflow of liquid. The contents of the container can then rush right through these nipples down through the T 17 and its lead-off 19. In many instances, it may be desirable to completely 10 remove the stem-turning arrangement after the vent has been completely closed. In order to accomplish this, it is only necessary to unscrew and remove the bushing 14. An ordinary plug can then be inserted into that 15 end of the T in order to protect the inside of the drain device. This would make the drain substantially fool-proof. On the other hand, the stem 12 could remain completely inserted in the drain device and some 20 suitable means could be provided for locking it in that position so that it would again be substantially fool-proof.

Figure 3 shows the use of a cap having a vent in the lateral side thereof. In order 25 to close the vent, the cap need only be turned tightly about the nipple 3.

Figures 5 and 6 illustrate the use of a plug, instead of a cap, fitting into the nipple. In Figure 5, the vent is in the nipple. 30 In Figure 6, the vent is in the plug. The threads within the nipple, and without the plug, may be so tapered that the vent is un-leakably closed when the plug is tightly drawn into the nipple. It is, of course, to be seen that the cap, plug or nipple may 35 have more than one vent. Any number of vents could be inserted. In fact, there is no reason why vents could not be employed in the nipple and cap or plug at the same time. 40 If only one vent is to be used, it can, of course, be made as large as the internal diameter of the nipple or cap or plug. A screening effect may be obtained by using a number of relatively smaller vents.

Figure 4 illustrates the use of a chamber device 21 about the cap 7, or plug 8, and vent 6, which is adapted to drain off the contents of the container at different levels within the container through the adjustable 45 conduit 22. The chamber 21, which may be a cylinder, is attached to the nipple 3 and locked by lock washer 10. This chamber might likewise be attached to the tank itself. In order to get at the cap 7, or plug 8, the 50 chamber 21 may have a head 22 made removable. The conduit 23 is suitably attached to the chamber 21, and preferably as close as possible to the end of the chamber attached to the nipple so that the strain 55 thereon may be as little as possible. This conduit 23 may be made to move from one level to another within the tank by a chain attached thereto leading up to the top of the container. In order that the cap, or plug, 60 and the nipple may not be entirely disengaged, the chamber 21 is made of such length that when the vent 6 is in the open position, the cap 7, or plug 8, rests against the end 22 of the chamber.

A glance at Figures 1 and 2 will show the 70 operation of this improved drain device in its simplest form. The liquid within the container will flow down through the vent 6 when the vent is in the open position. As soon as the cap or plug has been moved 75 back against the guard 9, the liquid is in a position to rush through the nipple 3. In order to allow a free unimpeded passage of the liquid through the drain device, the stem 12, in the case of a detachable arrangement, 80 may be withdrawn from the axial passage-way so that the head 11 of the stem will rest against the bushing 14. The escaping liquid then has a free outlet through 85 19. In order to shut off the flow of liquid from the container, it is only necessary to again push the stem 12 back through the axial passage of the nipples 18 and 3 so that the head 20 of the stem may engage the socket 90 11 of the cap or plug. An appropriate number of turns will again close the vent and, if desired, the stem 12 may then be detached from the socket 11 and completely removed from the draining device by unscrewing the 95 bushing 14.

In the case of the chamber arrangement adapted to drain strata of liquid from different levels of the container, all that is necessary is to lift, or lower, the adjustable conduit 22 to the level or stratum of liquid desired. The chamber and conduit are thus in such a position that the liquid of that particular level may flow readily into the chamber itself. In order to have this liquid 100 flow out of the draining device into the lead-off 19, it is only necessary that the vent 6 be opened by the cap 7, or plug 8, as above described.

It must be evident that numerous modifications of different features of this improved drain device are possible, such as are not described above, without departing from the spirit of my invention.

I claim:

1. A drain device of the non-freezing type 115 which comprises, a threaded stationary member having an axial passage therethrough, a threaded movable member operatively connected to said stationary member, the threads of the stationary and movable 120 members being in engagement with one another and so cut that said threads may be tightly and non-leakably drawn into engagement with one another, a vent leading to the axial passage of the stationary member, and means for rotating the movable member in 125 fixed longitudinal position relative to the stationary member to open and close the vent.

2. A drain device of the non-freezing type 130

which comprises, a threaded stationary member having an axial passage therethrough, a threaded movable member operatively connected to said stationary member, the threads of the stationary and movable members being in engagement with one another and so cut that said threads may be tightly and non-leakably drawn into engagement with one another, a vent leading to the axial passage of the stationary member, means for rotating the movable member in fixed longitudinal position relative to the stationary member to open and close the vent, and means to prevent the complete withdrawal of the movable member from the stationary member.

3. A drain device of the non-freezing type which comprises, a threaded stationary member having an axial passage therethrough, a threaded movable member operatively connected to said stationary member, the threads of the stationary and movable members being in engagement with one another and so cut that said threads may be tightly and non-leakably drawn into en-

gagement with one another, a vent leading to the axial passage of the stationary member, means for rotating the movable member in fixed longitudinal position relative to the stationary member to open and close the vent, and means for conducting the contents of a container from different levels to the vent.

4. A drain device of the non-freezing type which comprises, a threaded stationary member having an axial passage therethrough, a threaded movable member operatively connected to said stationary member, the threads of the stationary and movable members being in engagement with one another and so cut that said threads may be tightly and non-leakably drawn into engagement with one another, a vent leading to the axial passage of the stationary member, and detachable means for rotating the movable member in fixed longitudinal position relative to the stationary member to open and close the vent.

In testimony whereof I affix my signature.
JOSEPH L. HUTCHINGS.
